UNITED STATES PATENT OFFICE.

CARL A. MEILICKE, OF CHICAGO, ILLINOIS, ASSIGNOR TO MEILICKE CALCULATOR COMPANY, OF CHICAGO, ILLINOIS, A CORPORATION OF MAINE.

CALCULATOR.

1,079,712.

Specification of Letters Patent. Patented Nov. 25, 1913.

Application filed April 22, 1911. Serial No. 622,704.

To all whom it may concern:

Be it known that I, CARL A. MEILICKE, a subject of the King of Great Britain, residing at Chicago, in the county of Cook and 5 State of Illinois, have invented certain new and useful Improvements in Calculators, of which the following is a specification.

My invention relates to improvements in calculators and in some of its features more 10 particularly to time and interest calculators wherein the occurrence of Sundays and holidays is important to be noted.

One of the salient objects of my invention is to provide a simple and efficient machine 15 for the calendar indications and the calculation of interest, by mechanism improved in general arrangement and in detail.

A further object of my invention is to provide a machine wherein indicia of 20 calendar dates, holidays, and numbers are so correlated that the relation of any two of these factors to a given third factor may readily be ascertained by mechanical means.

In the drawings, wherein I have illustrated an embodiment of my invention, Figure 1 is a front view partly in elevation and partly in central vertical section of an interest calculating machine of my invention: Fig. 2 shows the casing in transverse vertical section on line 2--2 of Fig. 1 and the interior mechanism in elevation; Fig. 3 and Fig. 4 are details taken on lines 3--3 and 4--4, respectively, showing the adjustment detent; Fig. 5 is a fragmentary detail taken 25 from the right of Fig. 2; and Fig. 6 and Fig. 7 are details of a preferred holiday wheel and clip arrangement.

In the drawings, the machine is illustrated as affording a casing whereof 10 is a casting 30 base, 11 a front wall, 12 the reading face, 13 and 14 angular rear wall members, and 15 and 16 the detachable end walls. Within the casing, near its ends, are arranged the standards 17 and 18, secured to the base, and 40 each at its end provided with a bearing head 19, which with its complemental detachable cap 20, affords a smaller bearing aperture 21, and a larger bearing recess 22.

23 is a driving shaft, extending through 45 the casing from end to end, working in the bearings 21, and provided at its opposite extremities beyond the casing with the hand wheels 25--25.

26 indicates a hollow driven shaft journaled in the bearing recesses 22, and sur-

rounding the driving shaft 23, and upon the driven shaft 26 are mounted all of the movable indicator parts of the machine. The principal object of the double shaft arrangement is to permit the indicator parts to be 60 driven at a rate of revolution lower than that of the driving shaft 23, and to facilitate the application of hand wheels to the faster-traveling driving shaft at both ends of the machine. Between the driving shaft 23 and 65 the hollow driven shaft 26, I interpose a reduction gear arranged to drive both shafts in like directions.

27 indicates a gear, secured as at 28 on the driving shaft 23, beyond the standard 70 18, and meshing with a gear 29 mounted on a short jack shaft 30, carried by an arm 18' of the standard 18, said jack shaft bearing also a pinion 31 which meshes with the gear 32, keyed as at 33 upon the hollow shaft 26. 75 The gear wheel 32, fixed to one end of the hollow shaft 26 and a collar 34 fixed to the other end, leaves the said shaft 26 free to turn on its bearing regardless of pressure exerted on the parts 32 and 34 by the spring- 80 pressed parts on shaft 26, hereafter to be referred to.

At suitable distances from the ends of shaft 26 I secure thereto rimmed-spiders or carrying wheels 35 and 36, each having its 85 rim serrated, as at 35'--36' respectively, in crown form, and at suitable intervals on the shaft I provide other carrying wheels 37, so forming a skeleton frame on which is peripherally secured in cylinder form a chart or strip 40, having its meeting extremities 90 turned as at 41 (Fig. 2) into convenient notches in the rims of the supporting wheels, and secured in place by a wedge 42, preferably extending the full length of the chart and showing at its exterior as a line (see Fig. 1) which forms the datum line or starting point for numerical calculation. Thus, in effect, the chart 40 is an endless strip, and each of the other movable reading strips concentric or coaxial therewith is likewise effectively endless.

Along each edge margin of the chart 40, as indicated at 45 and 45', I provide in a peripheral column a numerical index, showing the number of days in the year, commencing with 1 adjacent the datum line, the space occupied by the wedge 42 representing the 365th day. These indices I may refer to as "number strips" for they may be used 105 110

regardless of the other indications on chart 40. The entire area of the chart between said marginal number strips may be regarded as divided into (imaginary) rectangular spaces arranged in longitudinal rows each corresponding with a number of the marginal column or number strip, and in circumferential columns of any desired number according to the limits within which 5 the machine shall work. Thus, in the ordinary interest calculators, such as herein specifically shown, the central area of the chart is occupied by a computed interest table 46, comprising, for instance, forty five 10 columns grouped into five divisions, each division including nine columns. In such arrangement, the five divisions may represent, say, 4%, 4½%, 5%, 5½%, and 6%; the nine columns of each division represent 100, 200, etc., to 900; and each space of the table has 15 printed therein the interest figured upon the amount characteristic of the particular circumferential column at the rate characteristic of the division containing the column 20 for the number of days indicated by the number, contained in the numerical table 45 or 45', appurtenant to the same longitudinal row. In this arrangement of the chart, my present machine substantially conforms with 25 the calculating machine shown in my prior Patent No. 914,439, dated March 19, 1909.

At each end of the rotatable shaft 26, I provide a rotatable calendar wheel, as indicated at 50 and 51, the rim surface of each 30 constituting a movable calendar strip, said 35 calendars having their month and day indications arranged thereon in reverse order with reference to each other, as in the calculating machine of my prior Patent No. 823,426, dated June 12, 1906. On each such calendar strip, the day-spacing corresponds 40 with the number-spacing on the number strip 45, and the month-name or abbreviation 45 preferably occupies a tabular division including all of the day spaces of the month. Each such calendar wheel is loosely mounted 50 on the shaft 26 and may be rotated relatively to the rotatable chart 40 for setting adjustment, but is normally carried in rotation with said chart through the engagement 55 of a suitable spring pawl or detent, carried by the calendar wheel with the crown ratchet or serrated edge of the chart drum. Specifically, the calendar wheel 50 on which 60 the date indications run backwardly with reference to the numbering on the chart 40 may conveniently be mounted contiguous to one end of the chart drum, and may be provided with a spring pawl 52, engaging the 65 serrated edge or ratchet 35' at the end of said drum. The forwardly reading calendar wheel 51 has its reading strip or rim spaced apart from the edge of the chart, but said wheel carries a 70 suitable spring pawl 52' for engagement

with the ratchet or serrated edge 36' of the chart drum. The teeth of the ratchets 35' and 36' are equal in number to the 365 spaces of the wheel and the co-operating parts of the spring pawls or detents are arranged always to seat accurately between teeth so that the spacings of the drum will, 75 always accurately align with spacings of the calendar strips.

Calendar wheel 51 is preferably provided 75 with a hub elongation 51', bearing loosely mounted thereon one or more holiday wheels herein shown as two in number and indicated as 53 and 54, the purpose of such duplication being to afford a "current year's" 80 holiday wheel, and a "next year's" holiday wheel.

The holiday wheels are preferably of substantially identical construction, having a rim or holiday strip 56, provided with 85 grooves 57 for the reception of marker clips 58 (see Figs. 6 and 7). Each clip is constructed for ready adjustment and removal, but to grip firmly its strip when properly placed. The form of clip shown, consisting 90 substantially of a U-shaped spring metal strip, I have found very satisfactory. The markers are preferably colored,—one color for Saturdays, one for Sundays, and another for special holidays. Each of the holiday wheels is carried in rotation in harmony 95 with the calendar wheel 51 by engagement of the respective spring detents 60 and 61 mounted on the calendar wheel with the respective toothed surfaces 53' and 54' of the 100 two holiday wheels. For convenience in placing and adjusting the markers 58 on the holiday wheels and adjusting the holiday wheels bodily relative to the calendar wheel, an aperture 63 is made in the wall 13 of the 105 casing, where said wall closely approaches the wheels, said aperture being normally covered by a cover plate 64.

The face 12 of the machine is provided with a face plate 65, bearing on its under 110 surface in alignment with the two calendar wheels 53 and 54, small brake shoes 66, each lifted normally from contact with its calendar wheel by its supporting spring 67, and arranged for depression into contact with the wheels by an appropriate brake button 68 or 69, extending through the face plate. Manifestly, when the brake for calendar wheel 50 is depressed by pressure applied to the brake button 69, rotation of the hand 115 wheel will rotate the drum 40, and the wheels at the right end of the casing, but the calendar wheel 50 will remain stationary until the brake is released. In similar manner, setting of the brake for wheel 51 will 120 hold stationary the calendar wheel 51, and its appurtenant holiday wheels 53 and 54, while the drum and the opposite calendar wheel are being rotated. Thus, each calendar wheel may easily be set to bring the in- 125 130

stant calendar date opposite the datum line 42 of the number strip and interest table, and the holiday wheels retain their set relation to the calendar wheels 51 throughout the entire normal operation of the machine. It will be understood, of course, that the markers 58 on the holiday wheel 53 may be set with reference to the calendar wheel to indicate every legal holiday for the current year, and the markers on wheel 54 correspondingly set to indicate each legal holiday of the next year. When the current year expires, the wheel 54 does not have its setting changed, but becomes the calendar wheel for the then current year, while the setting of the wheel 53 is changed throughout to correspond with the then succeeding year. It will be manifest that (except as to leap-years), the spacing of the Saturday and Sunday markers need never be changed but that by simply adjusting the holiday wheels bodily relative to the calendar wheel so that a Sunday marker stands opposite the appropriate date of the last Sunday of the year, all of the remaining Saturday and Sunday markers stand in proper arrangement, so that only the special markers for such holidays as January 1st, February 22nd, and the like, need be shifted in effecting the readjustment. In leap year, the holiday wheel is set properly to show the first Sunday in March and then all Sundays prior to that time must be moved one space to correspond with the appropriate dates and of course, in any numerical calculation which includes the 29th of February, allowance must be made of the fact that that date does not appear upon the calendar of the machine.

The face plate 65 has made therein a reading aperture 70, preferably covered with a glass sheet 71, and carries in suitable association with the rotatable members of the machine any suitable gage-means to define the reading line for convenient following of the longitudinal rows of figures on the rotatable parts, and preferably, also tabular matter for identifying the bases on which the circumferential columns of the chart are figured. Thus, as illustrated, the glass plate is underlaid with a shield 75, of paper, having a longitudinal reading slit, 76, just wide enough to display a row of spaces and longitudinally co-extensive with and parallel to a longitudinal row of data inclusive of the date indicia on the end calendar wheels 50 and 51. The ends of the paper screen 75 are preferably cut away as indicated at 77 to leave exposed enough of the calendar wheels for easy reading of a month name or abbreviation, which preferably reads circumferentially.

The surface of the shield 75 above and below the reading slot 76 preferably bears tabular matter or indicia, substantially as described in my prior Patent 914,439, indicating in major divisions, 80, the percentage basis on which the chart tabulations are figured, and on a scale 81, adjacent the lower lip of the slot, 76, the particular numbers from 100 to 900 upon which the corresponding columns on the chart 40 are figured. Above the reading slot 76 the shield preferably bears a table 82 of interest computations for different numbers of even years based upon the amounts and percentages shown in the tables 80 and 81.

For most calculations, the machine should be set so that the datum line 42 coincides with the instant date upon both calendar strips 50 and 51. To this end, the instant date on calendar 50 is brought into register with the reading slot 76 and then the brake for said calendar wheel is set by depressing the brake button 69. Thus, considerable force may be exerted upon the calendar wheel to hold it still, and as one of the hand wheels is rotated, rotatively moving the drum 40, the datum line 42 is brought into register with the reading slot 76, and the instant date space of the calendar. In similar manner, the other calendar strip 51 with its associated holiday wheels is set so that its indication of instant date aligns with the datum line 42. The holiday wheels, once set, are not disturbed for a year.

As the simplest example of the operation of my machine, assume, for instance, that January 17th, 1911, is the instant date, and that 5% interest on a 60-day note for \$100 is to be figured, and the date of payment of the note to be ascertained. The machine is properly set as heretofore described to bring the instant date on calendar strip 51 in register with line 42, the operator rotates either handle 25 until the number 60 on the number strip of the drum or chart (the chart itself physically forms the drum) 40 appears opposite the reading slot 76. Glancing then at the calendar wheel 51, and the current year holiday wheel 53, the operator observes that the 60 days expire on Saturday, March 18th, 1911, which is, for such transactions, a holiday in most States. Therefore, the operator rotates the drum farther until the first date not a legal holiday, according to the markers of the holiday wheel, appears in the reading slot 76. The actual future date of payment is thus ascertained to be March 20, 1911, so that interest must really be paid for 62 days. Now, by reading the figures of the computed interest table appearing through the reading slot 73 above the "100" column of scale 81, in the 5% division of scale 80, the operator learns instantly that the interest to be paid on said note amounts to \$00.861.

It will be obvious to those skilled in the art that special charts may be employed covering a wide range of mathematical calculations.

lations in which the relations between number of elapsed days, calendar dates, and holidays, enter into calculations; and that disregarding entirely the mathematical calculations upon the interest table, the association of a calendar strip with adaptable holiday markers on an adjustable holiday strip, and a number strip for showing elapsed days, constitute a device with many advantages for many different uses, and widely variable in form of construction without departure from the essence of the arrangement shown.

While I have herein described in considerable detail for the purpose of full disclosure one practical and operative embodiment of my invention, it will be understood by those skilled in the art that many changes in the arrangement and construction might be made without departure from the spirit of my invention and within the scope of the appended claims.

What I claim is:

1. In a device of the character described, a support, a calendar strip movably mounted thereon bearing consecutive date-indications, a holiday strip mounted to move with said calendar strip, and holiday markers adjustable upon said holiday strip into register with different dates of the calendar strip.
  2. In a device of the character described, a support, a calendar strip movably mounted thereon, a holiday strip mounted with respect to the calendar strip for adjustment relative thereto and to move therewith, and individually shiftable holiday markers carried by said holiday strip in register with respective dates of the calendar strip.
  3. In a machine of the character described, the combination of a support, means on said support, to indicate a reading position, a calendar strip bearing consecutive date indications mounted in said support for movement with respect to said reading position, and holiday markers for indicating holiday dates on said calendar strip mounted for movement in harmony with said calendar strip and for adjustment relative to said calendar strip.
  4. In a machine of the character described, the combination of a calendar strip bearing consecutive date indications, shiftable means associated with said calendar strip, bearing indications for register with different calendar strip dates to mark holidays, and a number strip having number spaces for register with the day spaces of the calendar strip and movable with respect to said calendar strip.
  5. In a machine of the character described, the combination of a support provided with means for indicating a reading position, an endless calendar strip having consecutively designated date spaces, an endless number strip having consecutively numbered spaces
- corresponding with the date spaces of the calendar strip, said calendar strip and number strip being movable with respect to each other to cause the respective number spaces to register with different date spaces, and both movable with respect to the support to present different spaces in reading position; and a holiday strip bearing indications of holidays registering with appropriate spaces of the calendar strip and movable therewith.
6. In a machine of the character described, the combination of a support provided with means for indicating a reading position, an endless calendar strip bearing consecutively designated date spaces, for a year, and endless number strip having numbered consecutive spaces corresponding with the date spaces of the calendar strip, said calendar strip and number strip being movable relative to each other to cause the respective numbered spaces to register with different date spaces, and movable relative to the support to bring different number and date spaces into reading position, and holiday markers associated with the calendar strip for normal movement therewith, and shiftable relative thereto.
  7. In a machine of the character described, the combination of a number strip and two reversely reading coaxially arranged calendar strips, a number strip having consecutive number spaces, means to support said strips for relative adjustment to cause any given number space to register with different date spaces of either calendar strip, and a separate holiday strip bearing indications of holidays adjustable with respect to one calendar strip.
  8. In a machine of the character described, the combination of a rotatable calendar wheel having a hub and bearing on its periphery a series of consecutively designated date spaces, a coaxial holiday wheel mounted on said hub, and holiday markers shiftable upon said holiday wheel for register with different selected dates of the calendar wheel.
  9. In a machine of the character described, the combination of a support provided with means for indicating a reading position, a calendar strip provided with consecutive date indications, a number strip provided with consecutive number indications, said two strips mounted to said support for movement with respect to each other and with respect to the reading position to bring any combination of date and number into reading position, a separate strip adjustable relative to the calendar strip and normally movable therewith, and shiftable holiday markers carried by the last said strip in register with appropriate dates of the calendar strip.
  10. In a time and interest calculating ma-

- chine, the combination of a casing having a sight opening to indicate reading position, an interest table rotatable in said casing, a coaxial calendar strip having consecutively 5 designated date spaces, movable with respect to the interest table and to the casing, means normally to connect said tables for movement together, adjustable to permit movement of one of said parts relative to 10 the other, and separately adjustable holiday indicating means carried in rotation by one of said parts.
11. In a machine of the character described, the combination of a rotatable calendar cylinder bearing on its periphery a 15 series of consecutively designated date spaces, a coaxial narrow cylinder movable in rotation with said calendar cylinder, and holiday marking clips spanning the periphery of said narrow cylinder and shiftable thereon for register with different date spaces.
12. In a machine of the character described, a casing provided with a sight 20 opening, a horizontal drive shaft freely rotatable in either direction extending through said casing, hand knobs for rotating same beyond both ends of the casing, a hollow driven shaft enveloping the driving shaft, 25 a reduction gear connecting said driving and driven shafts arranged to rotate said shafts in the same direction, and an indicating cylinder, having data to be brought
- to reading position with respect to the casing sight-opening, rotatable with said driven shaft.
13. In a machine of the character described, the combination of a casing, bearing members within the casing affording smaller shaft bearing-openings and larger 40 shaft-bearing-recesses, a drive shaft mounted in said smaller bearing-openings, and extending beyond the ends of the casing, exterior driving means associated with said drive shaft, a hollow shaft surrounding the 45 driving shaft, and journaled in said larger bearing-recesses, driving connections between said driving shaft and said hollow shaft, and indicating devices carried in rotation by said hollow shaft.
14. In a device for calculations involving the occurrence of Sundays and holidays, the combination of a movable number strip, a relatively movable calendar strip, and a 50 holiday strip separate from the calendar strip, said holiday strip having thereon indicia of Sundays and other holidays arranged for proper correspondence with date indications on said calendar strip.
- In testimony whereof I hereunto set my 55 hand in the presence of two witnesses.

CARL A. MEILICKE.

In the presence of—

GEO. T. MAY, Jr.,
MARY F. ALLEN.
